UNITED STATES PATENT OFFICE

CLEMENT BOOTH, OF CINCINNATI, OHIO, ASSIGNOR TO CINCINNATI GRINDERS INCORPORATED, OF CINCINNATI, OHIO, A CORPORATION OF OHIO

GRINDING MACHINERY

Application filed April 9, 1928. Serial No. 268,542.

This invention relates to improvements in grinding machinery and more particularly to what is known as the centerless type of grinding machinery.

The principal object of the present invention is the provision of an improved form of such machine particularly adapted for the production of the stem or barrel portion of drills or similar articles in a manner to render the same properly concentric as respects the tool engaging shank thereof.

A further object of the invention is the provision of a simple mechanism capable of ready application to present commercial grinders which will adapt same for satisfactory production of a second surface on a cylindrical member concentric or co-axial with a first surface or portion already formed thereon to within very fine limits of accuracy.

An additional object of the present invention is the provision of a novel and improved process for the complete production of drills or like members intended to have co-axial surfaces of revolution which are noncontinuous.

Other objects and advantages of the present invention should be readily apparent by reference to the following specification taken in conjunction with the accompanying drawings forming a part thereof, and it will be understood that I may make any modifications in the specific structural details hereinafter disclosed within the scope of the appended claims without departing from or exceeding the spirit of the invention.

Figure 1 is a front view of a machine embodying the invention.

Figure 2 is an enlarged view of the work supporting member with bracket and associate parts in section.

Figure 3 is a sectional view on the line 3—3 of Figure 2 looking in the direction of the arrows.

Figure 4 is a plan view of the work and fragmentary adjacent portion of the machine, parts of the latter being shown in section.

Figure 5 is a fragmentary sectional view

illustrating a further step in the process of production of a completed article.

Figure 6 is a similar fragmentary view at right angles to Figure 5.

Figure 7 is an enlarged semi-diagrammatic view illustrating the angular relationship between the several effective surfaces of work and positioning members.

In the drawings in which similar characters of reference are employed to denote corresponding parts throughout the several views, the numeral 10 designates the bed of a conventional grinder having mounted thereon the housing 11 for the grinding wheel 12 which is rotated at a high grinding rate of speed in the direction of the arrow on the grinding wheel housing. The bed is further formed with ways 13 for slide 14 which in turn is provided with the additional ways 15 for the regulating wheel 70 slide unit 16. This unit bears the regulating wheel 17 rotated at a slow work controlling rate of speed in the direction of the arrow indicated on its housing or guard.

Mounted on the slide 14 is a bracket 18 carrying the work rest blade 19 and the supplemental work rest unit 20. This unit has the upstanding lugs 21 and 22 to which are adjustably secured the out-board bearing plate 23 for the outer tapered shank portion 24 on the drill or like work piece 25. This member 23 is preferably formed with an inclined work supporting surface 26 whose angle corresponds substantially to that of the upper face of the work rest blade 19 and is in addition formed with a substantially vertical face 27 inclined at a slight angle or slightly curved to extend substantially parallel with the proximate portion of the regulating wheel. The height of the member 26 may be varied to properly support the work by suitable adjustment effected as by loosening of the clamp bolts 28 engaged in the slots 29 of support member 23. Likewise back and forth adjustment for proper relative positioning of the outer rest as respects the work rest blade and regulating wheel may be effected by loosening of bolt 30 and manipulation of adjusting screw 31 in threaded engagement with the base por-

tion of the fixture and rotatably associated with the slide 20 but held against axial movement relative thereto as will be readily apparent by reference to Figure 2.

5 In the utilization of this portion of the invention the stem or barrel of the drill or work piece 25 is placed in engagement with the upper face of the work rest blade 19 and actuated by gravity against the surface 10 of the regulating wheel 17. The slide 14 bearing the regulating wheel unit 16 and the work rest is then moved inward as by manipulation of pilot wheel 32 or other suitable mechanism pressing the portion of work 15 to be operated upon against the grinding wheel 12.

It will be understood particularly by reference to Figure 7 that it is necessary to produce on drills a slight clearance angle 20 which is to say that the diameter adjacent the shank is slightly less than that at the point. This means that there is normally a slightly greater amount of grinding to be performed at the shank end of the work 25 than has to be performed at the point and the particular form of outer work support is therefore particularly desirable in that the relationship between regulating wheel surface 17 and shank engaging surface 27 30 is such that undue canting of the work between the wheels is prevented due in spite of their tapered relationship to the resistance offered by the surface 27 to displacement of the shaft. At the same time the angle of surface 27 is such that when irregularities on the drill barrel are engaged by the regulating wheel tending to lift the work upward on the work rest to a wider portion of the grinding throat the outer end of the 35 work will also be correspondingly lifted. Consequently the work is so terminally supported at a predetermined point on the shank that both vertical tilting or dropping of the outer portion and lateral deflection is 40 prevented without in any wise interfering with the normal free floating movement of the work between work on the work rest and between grinding and regulating wheels.

Attention is invited to the fact that with 50 this arrangement of parts the outer end of the work piece is supported at two points which positively support this end concentric with the portion of the work piece within the grinding throat. From this it must follow, as in the case of drills, that the barrel 55 of the work piece or drill will run true to its outer or supporting end after such supporting end has been inserted within a holder or spindle.

60 In the carrying out of the improved process contemplated by the present invention the drill having been ground as just disclosed as respects its barrel portion is then reversed and the barrel portion within a suitable sleeve or supporting fixture 33 of

a size to just receive the largest diameter of said barrel portion and with the fixture held in a slightly canted position so as to form a line contact with one side of the cylindrical surface just completed. While so held the tapered shank portion is introduced into the throat of a centerless grinder such as is illustrated in Figure 1 between the grinding and regulating wheels, the regulating wheel having a rib portion 34 intended in the finished shank to contact with substantially the same portion of the shank as was previously engaged by the supporting plate 23 while the work rest also has a rib or upwardly projecting portion 35 correspondingly engaging the shank. These parts serve for final positioning of the tapered shank in the throat in which it is ground. Consequently the process as here disclosed consists in producing concentric 85 barrel and shank portions on twist drills or the like by successively floating the portions of the work to be ground on a work rest and between grinding and regulating wheels and employing a constant point on the work for positioning both portions thereof during the successive grinding operations. The specific mechanism for performing the second grinding operation has been here disclosed merely in its broadest sense for purpose of 95 understanding of the process involved inasmuch as the specific structural details of the particular machine form the subject matter of my co-pending application Serial No. 268,543, filed April 9, 1928.

From the foregoing description the improved process of successive concentric production of drills should be readily understood as well as the specific structural details of the machine utilized for performance of the first portion of the process.

I claim.

1. A machine for the production of substantially cylindrical work pieces including a work rest, a grinding wheel disposed at one side of the work rest and having its operative face moving at a high grinding rate of speed in the direction of the work rest, a work regulating member disposed on the opposite side of the work rest and having its surface moving in the opposite direction from that of the grinding wheel to control the rate of rotation of a work piece on the machine, the rest having a work engaging surface ascending toward the grinding wheel, and a steadyng member for and overhanging portion of the work having a work engaging surface substantially parallel with that of the work rest and a second surface substantially parallel with that of the regulating member for simultaneous engagement with an overhanging portion of the work to steady the latter during grinding.

2. A machine for the centerless production of work with portions of different diameters

including opposed grinding and regulating wheels forming a work receiving throat therebetween, a work rest blade disposed in the throat between the grinding and regulating wheels, and an out-board fixture for support of a portion of the work of different diameter having a supporting surface extending substantially parallel with that of the work rest but off-set an amount equivalent to the difference in radii of the work at the grinding and support engaging portions thereof, whereby the out-board support will continuously properly engage the overhanging portion of the work during movement of the work on the work rest blade.

3. A machine for the centerless production of work with portions of different diameters including opposed grinding and regulating wheels forming a work receiving throat therebetween, a work rest blade disposed in the throat between the grinding and regulating wheels, and an out-board fixture for support of a portion of the work of different diameter having a supporting surface extending substantially parallel with that of the work rest but off-set an amount equivalent to the difference in radii of the work at the grinding and support engaging portions thereof, whereby the out-board support will continuously properly engage the overhanging portion of the work during movement of the work on the work rest blade, said out-board support having a second portion at the regulating wheel side thereof similarly off-set as respects the surface of the regulating wheel and substantially parallel therewith to limit the movement of the overhanging portion of the work in the direction of the regulating wheel, and means for transversely shifting said outer work support.

4. A machine for the centerless production of work with portions of different diameters including opposed grinding and regulating wheels forming a work receiving throat therebetween, a work rest blade disposed in the throat between the grinding and regulating wheels, an out-board fixture for support of a portion of the work of different diameter having a supporting surface extending substantially parallel with that of the work rest but off-set an amount equivalent to the difference in radii of the work at the grinding and support engaging portions thereof, whereby the out-board support will continuously properly engage the overhanging portion of the work during movement of the work on the work rest blade, and means for adjusting the relative height of the work rest blade and said outer supporting member.

5. A machine for the centerless production of work with portions of different diameters including opposed grinding and regulating wheels forming a work receiving throat

therebetween, a work rest blade disposed in the throat between the grinding and regulating wheels, an out-board fixture for support of a portion of the work of different diameter having a supporting surface extending substantially parallel with that of the work rest but off-set an amount equivalent to the difference in radii of the work at the grinding and support engaging portions thereof, whereby the out-board support will continuously properly engage the overhanging portion of the work during movement of the work on the work rest blade, said out-board support having a second portion at the regulating wheel side thereof similarly off-set as respects the surface of the regulating wheel and substantially parallel therewith to limit the movement of the overhanging portion of the work in the direction of the regulating wheel, and means for transversely shifting said outer work support.

6. A machine for the centerless production of work with portions of different diameters including opposed grinding and regulating wheels forming a work receiving throat therebetween, a work rest blade disposed in the throat between the grinding and regulating wheels, an out-board fixture for support of a portion of the work of different diameter having a supporting surface extending substantially parallel with that of the work rest but off-set an amount equivalent to the difference in radii of the work at the grinding and support engaging portions thereof whereby the out-board support will continuously properly engage the overhanging portion of the work during movement of the work on the work rest blade, means for adjusting the relative height of the work rest blade and said outer supporting member, and means for transversely adjusting the out-board work supporting member to insure proper relationship between the regulating wheel surface and the corresponding work engaging surface on the support.

7. A machine for the centerless production of work with portions of different diameters including opposed grinding and regulating wheels forming a work receiving throat therebetween, a work rest blade disposed in the throat between the grinding and regulating wheels, an out-board fixture for support of a portion of the work of different diameter having a supporting surface extending substantially parallel with that of the work rest but off-set an amount equivalent to the difference in radii of the work at the grinding and support engaging portions thereof whereby the out-board support will continuously properly engage the work rest blade, means for adjusting the relative height of the work rest blade and said outer supporting member, means for transversely adjusting the out-board work supporting member to insure proper relationship between the

regulating wheel surface and the corresponding work engaging surface on the support, and means for vertically adjusting said support to correspondingly position the angular portion thereof, relative the angle top work rest blade when the regulating wheel and corresponding surface of the support are in proper relationship.

8. In a centerless grinder the combination 10 of a pair of opposed grinding and regulating wheels forming a grinding throat therebetween, a work rest blade subtending the grinding throat having a surface for supporting a work piece in engagement with 15 the said grinding and regulating wheels, an outboard support exterior of the grinding throat and independent of the work rest blade having a supporting surface extending in a plane parallel with the supporting surface of the work rest blade, and means supporting said blade and outboard support for adjustment one with respect to the other while maintaining said parallel relationship of their surfaces.
9. In a centerless grinder the combination 20 of a pair of opposed grinding and regulating wheels having their proximate points spaced from one another, a work rest blade below the grinding and regulating wheels 25 and with the said wheels forming the three point grinding throat for the work, an outboard guide and supporting member having a portion contacting the work at a point in a plane parallel with the point of contact of 30 the regulating wheel with the work, and means supporting said blade and outboard support for adjustment one with respect to the other while maintaining said parallel relationship of their surfaces.
10. In a centerless grinder the combination 35 of a pair of opposed grinding and regulating wheels having their proximate points spaced from one another, a work rest blade below the grinding and regulating wheels 40 and with the said wheels forming the three point contact grinding throat for the work, an outboard guide and supporting member for engagement with the work exterior of the grinding throat having portions contacting therewith at points parallel with the points of contact of the grinding throat, and means for adjusting the operative position of the outboard support relative to the grinding throat while maintaining said parallel relationship between the points of contact of said outboard support and grinding throat.
11. In a centerless grinder the combination 45 with a bed, of a pair of opposed grinding and regulating wheels carried thereby and forming a grinding throat therebetween, a bracket carried by the bed beneath the grinding throat, a work rest blade supported by the bracket for peripheral engagement 50 with a work piece, an outboard support ex-

tending from the bracket and including a carrier, an outboard work rest on the carrier having supporting portions for engagement with the work at points parallel with the points of contact between the work and the work rest whereby to support the outer end of the work concentric with the portion within the grinding throat, and means for adjusting the carrier relative to the bracket to vary the operative position thereof while maintaining the parallel relationship of the points of contact of the several work rest members.

12. In a centerless grinder the combination 70 with a bed, of a pair of opposed grinding and regulating wheels carried thereby and forming a grinding throat therebetween, a bracket carried by the bed beneath the grinding throat, a work rest blade supported by the bracket for peripheral engagement 75 with a work piece, an outboard support extending from the bracket and including a carrier, an outboard work rest on the carrier having supporting portions for engagement with the work at points parallel with the points of contact between the work and the work rest whereby to support the outer end of the work concentric with the portion within the grinding throat, means for adjusting the carrier relative to the bracket to vary the operative position thereof while maintaining the parallel relationship of the points of contact of the several work rest members, and means for locking the carrier in its adjusted 80 positions.

13. In a centerless grinder the combination 85 of a bed, a pair of opposed grinding and regulating wheels having their proximate surfaces spaced from one another to form a grinding throat, a slide for one of the wheels for actuating said wheel toward and from the remaining wheel, a supporting block carried by the slide beneath the grinding throat, a work rest blade having a supporting surface carried by the block for peripherally supporting a work piece during grinding, a carrier member adjustably supported by the block, an outboard 90 work rest member supported by the carrier and having a portion for contacting the work at a point parallel with the supporting surface of the blade to hold the work remote from the grinding throat concentric with the portion of the work within the grinding throat, and means for adjusting the outboard work rest member relative to the carrier to vertically adjust the work rest blade and work rest member relative to one another and to laterally adjust the carrier relative to the supporting block to laterally adjust the work rest blade and work rest member relative to one another all while maintaining the parallel relationship of the 95 100 105 110 115 120 125 130

points of contact of said work rest blade and work rest member.

14. In a centerless grinder the combination of a bed, a pair of opposed grinding and regulating wheels having their proximate surfaces spaced from one another to form a grinding throat, a slide for one of the wheels for actuating said wheel toward and from the remaining wheel,
- 10 a supporting block carried by the slide beneath the grinding throat, a work rest blade having a supporting surface carried by the block for peripherally supporting a work piece during grinding, a carrier member adjustably supported by the block, an outboard work rest member supported by the carrier and having a portion for contacting the work at a point parallel with the supporting surface of the blade to hold
- 15 the work remote from the grinding throat concentric with the portion of the work within the grinding throat, means for adjusting the outboard work rest member relative to the carrier to vertically adjust the
- 20 work rest blade and work rest member relative to one another and to laterally adjust the carrier relative to the supporting block to laterally adjust the work rest blade and work rest member relative to one another
- 25
- 30 all while maintaining the parallel relationship of the points of contact of said work rest blade and work rest member, and means for locking the outboard work rest and carrier in their adjusted positions.

35 In testimony whereof I affix my signature.
CLEMENT BOOTH.
